Inventor:

Nelson Long,

Myself
W. G. Fife Jr.

United States Patent Office.

NELSON LONG, OF WATERTOWN, NEW YORK.

Letters Patent No. 78,300, dated May 26, 1868.

IMPROVED APPARATUS FOR ROLLING DOUGH.

The Schedule referred to in these Letters Patent and making part of the same.

TO WHOM IT MAY CONCERN:

Be it known that I, NELSON LONG, of Watertown, in the county of Jefferson, and State of New York, have invented certain new and useful Improvements in Apparatus for Rolling Dough; and I hereby declare the following to be a full, clear, and exact description of the same, reference being had to the accompanying drawings, in which—

Figure 1 is a perspective view of an apparatus made in accordance with my invention.

Figure 2 is a side view of the same.

Figure 3 is a longitudinal section of the auxiliary roller for graduating the distance of the dough-roller from the base-board.

My invention consists essentially of an apparatus for rolling dough or other material, in which the board or receptacle upon which the material is spread, is combined with a traversing-roller mounted in a frame adjustable to different heights above the dough-board, and sliding in ways or guides parallel with said board.

And my invention consists further in the means, hereinafter specified, for graduating the distance between the traversing-roller and dough-board, so that the material to be rolled may be spread into a sheet of any desired degree of thickness.

To enable those skilled in the art to understand and use my invention, I will proceed to describe the manner in which the same is or may be carried into effect, by reference to the accompanying drawings.

The board A, upon which the material to be rolled is placed, may be of any ordinary or suitable shape and construction. It is provided with side-boards, B, which serve a double purpose—preventing the dough from being squeezed out laterally from under the roller, and at the same time affording a means of regulating the position of the dough-roller with respect to the board. This roller C is mounted in the lower part of a frame whose two side-pieces, D, are pivoted or hinged to blocks, a, which slide in grooves or ways, b, formed in the side-boards B, parallel with the face of the board A. The side-pieces D are connected by cross-bars, E, the upper of which forms the handle by which the frame, and the roller which it carries, is drawn to and fro over the surface of the board A.

It will be seen that the roller-frame is capable of two distinct motions—a sliding movement, due to its connection with the blocks a, which slide backwards and forwards in the grooves b, and a swinging movement, resulting from its being pivoted or hinged to the blocks a; and thus, while moving the whole length of the board, it can be raised to any desired height above the same. In order to effect, with certainty and ease, this adjustment of the frame and roller, I prefer to employ one of the two arrangements shown in the drawings.

In the one case the upper face of each side-board, B, should be composed of a separate and independent plate or strip, F, provided on the under side with a series of inclined shoulders or projections, e, which are received in a series of correspondingly-inclined or sloping notches or recesses, d, formed in a movable bar, G, which lies in a shelf or recess, formed for its reception, in the side-board B. The bar G is somewhat shorter than the recess in which it lies, so as to be capable of a longitudinal play therein, which is effected by means of an adjusting or set-screw, f, which passes through a part of the board into the end of the bar. When the screw is turned the bar G will be drawn towards or away from the front of the apparatus, according to the direction in which the screw is revolved. When drawn towards the front of the machine, as shown in fig. 1, the shoulders e will fit snugly in the recesses d, and the plate F will be at its lowest point. When, however, the screw is turned so as to move the sliding bar G in the opposite direction, as indicated in fig. 2, the inclined shoulders e will be gradually moved out from the recess d until they rest upon the top of the bar G. The plate F will consequently be raised, so that the auxiliary roller H, which is mounted in the traversing-frame above the roller C, and is intended to bear upon and move over the plates F, will be elevated to a greater height above the board A, and will, consequently, cause the elevation of the frame and traversing-roller with which it is connected. In this manner, therefore, by means of the adjusting-screw f, the distance between the roller C and board A may be regulated and determined with ease.

In the other case, instead of employing the parts *e* & *d*, I effect the same result by combining with the roller *H* in the traversing-frame the means requisite for effecting the adjustment of the dough-roller *C*. To this end I mount the journals of the roller *H* in elongated bearings, *g*, as shown in fig. 3, and with each bearing I combine an adjusting-screw, *h*, passing down into the bearing from the upper side of the frame. The tendency of the pivoted roller-frame to swing downwards, induces a pressure of the roller *H* against the top of its bearings, and the pressure of the hand of the operator upon the rail *E*, in moving the frame to and fro, also forces up the rollers, so that its journals will be always in contact with the broad base of the set-screws. It will be seen, therefore, that by raising or lowering the screws, the roller *H* will be raised and lowered in its bearings, so that by this means the position of the roller *C* may be readily adjusted with respect to the dough-board.

When the adjusting-devices *F* and *G* are employed, the auxiliary roller *H* need not be mounted in adjustable bearings, and it may even be dispensed with altogether, the journals or hubs of the roller *C* in such case bearing upon the plates *F*. I prefer, however, to use the roll *H*, as thereby the main roller is left entirely free, to act upon the dough or other material.

The manner of operating the apparatus is too obvious to need explanation.

Having, therefore, described my invention, and the manner in which the same is or may be carried into effect, what I claim, and desire to secure by Letters Patent, is—

1. The combination, with the board or receptacle for holding the dough or other material, of the dough-roller, and the sliding or transverse frame for supporting the same, hinged or pivoted in the manner described, so as to be adjustable to different heights above the said board or receptacle, substantially in the manner and for the purposes shown and specified.
2. In an apparatus, such as described, I claim the combination, with the auxiliary roll and the elongated bearings formed for its reception in the sliding frame, of adjusting or set-screws, or equivalent means for regulating the position of the journals of the roll in their bearings, substantially in the manner and for the purposes shown and set forth.
3. The combination, with the side-boards, which form the bearings for the sliding frame, of the top plates provided with inclined projections, *e*, as described, and the correspondingly-notched sliding bars, and its adjusting-screws for raising and lowering said top plates, under the arrangement and for operation as herein shown and set forth.

In testimony whereof, I have signed my name to this specification before two subscribing witnesses.

NELSON LONG,
